HERMAN GERBER, OF PROVIDENCE, RHODE ISLAND, ASSIGNEE TO CROMPTON & KNOWLES LOOM WORKS, OF WORCESTER, MASSACHUSETTS, A CORPORATION OF MASSACHUSETTS

THREAD HOLDER FOR WEFT-REPLENISHING LOOMS

Application filed February 26, 1929. Serial No. 342,791.

This invention relates to thread holders for weft replenishing looms and it is an important object of the invention to provide an improved and convenient weighted element to which the weft ends of reserve bobbins may be attached.

In the usual form of multicolor weft replenishing mechanisms reserve bobbins are held in several vertical parallel stacks and the ends of the filling or weft ends extending from the bobbins are secured to some fixed point. As the bobbins descend in their stacks the weft ends become slack and unless some means is provided for keeping them taut they are likely to be engaged by the lay or some other part of the loom and be broken. It is an important object of my present invention to provide a simple and convenient form of weighted element so constructed as to afford a ready means for attaching the weft ends thereto, the element preferably comprising a wire having a pair of angularly disposed elements around which the weft ends may be wrapped.

It is a further object of my invention to provide a tensioning weight guided at a point intermediate its ends and connected at its upper end to the weft threads, the weight being effectively held against objectionable vibration, but subject to slight vibration to assist in straightening the weft ends.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is a top plan view of the outer end of a multicolor weft replenishing mechanism having my invention applied thereto,

Fig. 2 is a front elevation of the mechanism shown in Fig. 1, the lay and certain parts associated therewith being added,

Fig. 3 is a vertical section on line 3-3 of Fig. 2 looking in the direction of the arrows,

Fig. 4 is a detailed horizontal section looking down along line 4-4 of Fig. 3 in the direction of the arrows, and

Fig. 5 is a front elevation of one of the weighted elements forming an important part of my present invention.

Referring particularly to Figs. 1 and 2 I have shown a magazine frame M having vertical slots 10 from which extend the weft ends W. The bobbins B are located as set forth herein in four different stacks, the tips 11 of the bobbins being guided by slots 12 formed in the magazine frame. The magazine includes in its construction front and rear tie rods 13 and 14, respectively. The lay L moves back and forth under the magazine and carries the usual shuttle S which is propelled by the picker stick 15.

The matter thus far described is of common construction and for a further description of its construction and operation reference may be had to Patent No. 1,030,748.

In carrying my present invention into effect I extend the tie rod 14 as at 20 and mount for sliding adjustment therealong the head 21 of a vertical rod 22. Said head and rod are held in adjusted longitudinal position with respect to the extension 20 by means of set screw 23.

Slidably mounted for vertical adjustment on the rod 22 is a hub 24 held in position by set screw 25. Extending horizontally and forwardly in this instance from the hub 24 is a rod 26 bent at its forward end as at 27 and extending rearwardly as at 28. The portion 28 is preferably between the magazine and the main part of the rod 26 and has a pair of diagonally extending positioning pins 29 which have vertical substantially parallel portions 30 between which lie all of the weft ends W.

Projecting upwardly from the rod 26 is a plurality of pairs of guide pins, there being one pair for each stack of bobbins. These pairs, designated generally at 31, 32, 33 and 34, respectively, may be distributed along the main part of the rod 26 and are disposed both behind and in front of the positioning pins 29. The guide pins may be set into the rod 26 at an angle as suggested in Fig. 3 and the pins of each pair are spaced apart a slight distance to confine the respective weft ends to a small portion of the bar 26.

The lower end of the bar 22 may be threaded as at 40 and have mounted thereon upper and lower nuts 41 and 42, respectively, between which lies one end of a guide plate 43 shown more particularly in Fig. 4. The bar 22 extends through the guide plate and the latter is held in adjusted vertical position by means of the nuts. The plate is provided with a plurality of spaced non-circular, preferably elongated apertures 44, 45, 46 and 47 which lie preferably directly under the pairs of pins 31, 32, 33 and 34, respectively. The plate as shown in Fig. 1 extends substantially parallel to and under the rod 26.

15 The weighted elements which are illustrated particularly in Fig. 5 are formed preferably of a single piece of wire which is bent so as to have two relatively long parallel sides 50 and 51 which are located at the left and 20 right hand sides, respectively, of the element as viewed in Fig. 1. The upper end of the side 51 is bent downwardly and to the right to form a prong 52 inclined with respect to the side 51. The other side 50 is bent back 25 on itself as at 53 and then projects upwardly and to the right to form a second prong 54 diagonal with respect to the portion 53. The latter portion is preferably in alignment with the side 51 so that the ends 52 and 54 are 30 substantially symmetrical about a horizontal line passing centrally through the opening 55 between the bent ends of the wire. The prongs 52 and 54, being formed of wire, form a slightly resilient holder around which the 35 weft ends may be wrapped, and said ends by extending in opposite directions serve to retain the mass of weft which is wound into the notches 56.

As shown in the right hand end of Fig. 4 40 the parallel sides 50 and 51 of the weighted element may lie respectively in the opposite ends of one or another of the slots formed in the guide. The slots serve to hold the weighted element against rotation so that 45 the prongs 52 or 54 are always in substantially the same position, namely, projecting outwardly or toward the side of the loom to be accessible as shown in Fig. 2. If desired auxiliary U-shaped weights 60 may be looped 50 through the bottoms of the weighted elements as shown in Fig. 3. It will also be seen that the guide plate restrains vibration of the elements 50 by engaging the latter intermediate their ends and that vibration of the upper 55 ends of the elements is resisted by the weft threads. In this way a single guide is found to be sufficient for the element 50.

In operation, when a new supply of bobbins is being placed in the magazine, the weighted 60 elements will be raised to their highest position and the several weft ends from the new bobbins wrapped around the prongs 52 and 54. Said ends will extend from the bobbins and all lie between the positioning pins 29 65 and then will extend to the particular pair of

guide pins corresponding to the stack from which the weft ends are drawn. Thereafter, as successive transfers occur and the bobbins move downwardly, the weighted elements will also descend, acting to keep the weft ends taut so that as the lay moves back and forth it will not become entangled with the weft ends.

70 From the foregoing it will be seen that I have provided a very simple form of thread holder for weft replenishing looms having a weighted element formed of a single piece of wire so constructed as to have oppositely extending ends to define means for holding a mass of yarn. It will also be seen that each weighted element has the lower portion thereof of a general form other than circular to be received by non-circular openings in the guide plate to keep the yarn engaging portion of the weight always in substantially the same position where it is readily accessible. It will also be seen that the guides 29 form a guide common to all the weft ends so that no matter through which of the pairs of pins the threads extend they will always be held in substantially the same position with respect to the lay so as to effect proper threading of the shuttle.

75 It will also be seen that the weighted elements 50, while being held against undue vibration which would result in entanglement of the several groups of weft ends, are nevertheless free to vibrate to a limited extent so as to subject the weft ends to repeated strains the effect of which is to straighten the threads should several of the threads become entangled and serve to prevent the weight from falling to its proper position to tension the lowest threads.

80 Having thus described my invention it will be seen that changes and modifications may be made therein by those skilled in the art without departing from the spirit and scope of the invention and I do not wish to be limited to the details herein disclosed, but what I claim is:

1. In a weft replenishing mechanism having reserve bobbins from which extend weft ends, a support for the weft ends, a weighted element having oppositely extending prongs adjacent the upper end thereof to which the weft ends are secured, and a guide through which the weighted element extends, the element extending above and below the guide member and being restrained as to vibration by said guide member.

85 2. In a weft replenishing mechanism having reserve bobbins from which extend weft ends, a support for the weft ends, a weighted element having oppositely extending prongs adjacent the upper end thereof to which the weft ends are secured, and a guide through which the weighted element extends, the latter extending above and below the guide member and being restrained as to vibration 90

by said guide member, said weighted element being formed of a single piece of wire and the prongs being defined by the ends of the wire.

5. In a weft replenishing mechanism having reserve bobbins from which extend weft ends, an elongated support substantially horizontal and over which the weft ends extend, a guide member below and substantially parallel to the support, and a weighted element positioned by the guide and restrained against vibration thereby, the upper end of the weighted element being attached to the weft ends, and guide pins on the first guide member to confine lateral movement of the weft ends along the first named guide to keep said weft ends properly placed with respect to the weighted element.

20. In a weft replenishing mechanism having reserve bobbins from which extend weft ends, a supporting rod, a guide plate, guide pins on the rod defining a space between which weft ends may extend, an opening in the plate located substantially below the 25 guide pins, and a weighted element extending through the opening in the guide plate and having the upper end thereof attached to the weft ends which extend between the guide pins, the latter directing the weft ends 30 toward the weighted element so that the element is disposed substantially vertically, the weighted element tending to keep the weft ends taut.

25. In a weft replenishing mechanism having reserve bobbins from which extend weft ends, a support member over which the weft ends extend, a guide plate below said member having a non-circular opening therein, a weighted element extending through the 40 opening and having prongs disposed in a plane transverse of the guide member, said non-circular opening cooperating with the weighted element to hold said prongs in the plane which is transverse of the guide member, the weft ends being secured to the prongs 45 and the element tensioning the weft ends.

In testimony whereof I have hereunto affixed my signature.

HERMAN GERBER.
